UNITED STATES PATENT OFFICE.

EARL M. STEVENS, OF CHICAGO, ILLINOIS.

DESIGN FOR A JAR.

Application filed November 3, 1923. Serial No. 7,670. Term of patent 14 years.

To all whom it may concern:

Be it known that I, EARL M. STEVENS, a resident of the United States, residing at 2838 Cambridge Avenue, in the city of Chicago, county of Cook, and State of Illinois, have invented a new, original, and ornamental Design for Jars, of which the following is a specification, reference being had to the accompanying drawing, forming part thereof.

Figure 1 is a top plan view of a jar embodying my new and original design.

Figure 2 is a side elevation of same.

I claim:

The ornamental design for a jar as shown. In witness whereof, I affix my signature.

EARL M. STEVENS.
